(57) **CLAIM**

(*) Term: **14 Years**

The ornamental design for beverage container protective end
cap assembly, as shown and described.

(21) Appl. No.: **29/241,524**

DESCRIPTION

(22) Filed: **Oct. 28, 2005**

FIG. 1 is a perspective view of beverage container protective
end cap assembly depicting the new design;

(51) LOC (8) Cl. **09-07**

FIG. 2 is a front elevational view thereof, depicting
container caps and spout on the top cap;

(52) U.S. Cl. **D9/447; D9/454**

FIG. 3 is a rear elevational view thereof, depicting the
opposite elevational view of the depicted caps in FIG. 2;

(58) Field of Classification Search D9/447,
D9/444, 440, 436, 435; D7/900, 619.1, 396.2,
D7/392.1, 300.2; 220/713, 711, 709, 705,
220/253

FIG. 4 is a right side elevational view thereof, the opposite
left side elevation view being a mirror image;

See application file for complete search history.

FIG. 5 is a top plan view of a top cap thereof; and,
FIG. 6 is a bottom plan view of a bottom cap thereof.
